ATTORNEY.

UNITED STATES PATENT OFFICE

LOUIS CHASE, OF ATLANTIC, MASSACHUSETTS

OIL CAN FOR EJECTING LIQUIDS

Application filed February 2, 1927, Serial No. 165,481. Renewed August 19, 1929.

This invention relates to a novel and improved force-feed, hand-operated dispensing device for dispensing liquids such as oil. The invention will be best understood by reference to the following description, when taken in connection with the accompanying drawings of one specific embodiment thereof, while its scope will be more particularly pointed out in the appended claims.

10 In the drawings:

Fig. 1 is an elevation of a dispensing device exemplifying the invention, partly broken away and partly in vertical section the better to illustrate the invention;

15 Fig. 2 is a bottom plan of the device with the lower part removed; and

Fig. 3 is a vertical, sectional view, illustrating a modification of the spring which tends to move one of the telescopically arranged parts outwardly with relation to the other.

Referring to the drawings, and to the embodiment of the invention which is illustrated therein, there is shown a dispensing device 10, comprising an outer, cup-like cylinder 11, and an inner, inverted cup-like piston 15, telescopically arranged within said cylinder and having a reasonably snug working fit therein. The cylinder and the piston 20 together constitute a reservoir for the liquid to be dispensed. The piston presents a nozzle 17, through which the liquid is dispensed from the reservoir.

The cylinder and piston are provided with 25 cooperative means normally to limit outward movement of the piston relatively to the cylinder, said means, in the present example, comprising an annular shoulder 13 formed on one part, herein the cylinder, engaged by 30 one or more, herein three appropriate detents or stops 20, which are laterally displaceable from the shoulder to permit complete withdrawal of the piston when the reservoir is to be refilled. In the present embodiment, 35 these detents or stops are resiliently mount-

ed, so that they are displaced by the mere application of a sufficient amount of force. This is conveniently accomplished in the present embodiment by making each detent or stop as a part of a spring 18, suitably secured to the piston, as by a rivet 19. Herein, the shoulder 13 is conveniently formed by providing the cylinder 11 with an annular bulge 12.

Appropriate resilient means are provided tending to thrust the piston outwardly from the cylinder and yieldingly to resist inward movement of the piston, said means being in the form of one or more springs, herein three springs 21 (see Fig. 1), or springs 18^a (see Fig. 3), conveniently formed as integral parts of the detents 20 and springs 18, and adapted to rest upon the bottom 14 of the reservoir 11. In the form shown in Figs. 1 and 2, each spring has an outwardly directed 50 free end 22, while in the form shown in Fig. 3, the ends of the springs 18^a are inwardly directed. In any case, the outward thrust of the spring or springs normally is resisted by the cooperative action of the detents or 55 stops 20 and the shoulder 13. On the other hand, when the operator squeezes the cylinder and piston, one toward the other, to expel liquid from the reservoir through the nozzle, the springs yield. Inward movement of the piston 60 relatively to the cylinder is conveniently limited by providing the piston with a laterally projecting annular flange or bead 16, which strikes the upper edge of the cylinder. This bead also strengthens the piston 65 and resists deformation of the same; it also forms a convenient shoulder for engagement with the fingers, to prevent the device from slipping through the fingers, which may be wet with oil or other liquid. Furthermore, 70 the shoulder may be availed of to rest in or upon an appropriate support.

To catch and retain liquid, and to prevent the same from running down about the outer surface of the cylinder, the piston and cylin- 75

der are cooperatively formed and arranged, as by providing the piston with a reduced portion 15^a, to provide a liquid-receiving groove when the piston is thrust inwardly. 5 This liquid works inwardly between the surfaces of the piston and cylinder, and produces a liquid seal which tends to prevent leakage of liquid from the reservoir when the latter is inverted.

10 The reservoir may be filled by pulling the piston out of the cylinder, and then pouring the liquid into the latter, after which the piston is introduced into the cylinder and pushed against the springs until the detents 15 or stops snap into place beneath the annular shoulder.

Having thus described one embodiment of the invention, but without limiting myself thereto, what I claim and desire by Letters Patent to secure is:

20 1. In a forced-feed, hand-operated dispensing device, the combination of two telescopically arranged parts constituting a reservoir for the liquid to be dispensed, a nozzle through 25 which the liquid is dispensed from said reservoir, and means normally to limit outward movement of one of said parts relatively to the other, said means having provision to permit separation of said parts for the filling 30 of said reservoir by merely moving one of said parts relatively to the other.

2. In a force-feed, hand-operated dispensing device, the combination of two telescopically arranged parts constituting a reservoir for the liquid to be dispensed, a nozzle through 35 which the liquid is dispensed from said reservoir, and spring detent means normally to limit outward movement of one of said parts relatively to the other, and adapted to yield to permit complete withdrawal of one 40 of said parts from the other.

3. In a force-feed, hand-operated dispensing device, the combination of two telescopically arranged parts constituting a reservoir for the liquid to be dispensed, a nozzle through 45 which the liquid is dispensed from said reservoir, one of said parts presenting a shoulder, limiting means carried by the other of said parts to cooperate with said shoulder to limit outward movement of one of said parts relatively to the other, said limiting means being movable laterally with relation to said shoulder into and out of cooperation with the latter in a direction transverse to said 50 movement, and resilient means tending to maintain said limiting means in engagement with said shoulder.

4. In a force-feed, hand-operated dispensing device, the combination of two telescopically arranged parts constituting a reservoir for the liquid to be dispensed, a nozzle through 55 which the liquid is dispensed from said reservoir, cooperating means on said parts normally to limit outward movement of one of said parts relatively to the other, said

cooperating means being relatively movable into and out of engagement with each other in a direction transverse to said movement, and resilient means tending to move one of said parts outwardly with relation to the other. 70

5. In a force-feed, hand-operated dispensing device, the combination of two telescopically arranged parts constituting a reservoir for the liquid to be dispensed, a nozzle through 75 which the liquid is dispensed from said reservoir, cooperating means on said parts normally to limit outward movement of one of said parts relatively to the other, said means having provision at will to permit complete withdrawal of one of said parts from the other, and resilient means tending to move one of said parts outwardly with relation to the other:

6. In a force-feed, hand-operated dispensing device, the combination of two telescopically arranged parts constituting a reservoir for the liquid to be dispensed, a nozzle through 80 which the liquid is dispensed from said reservoir, one of said parts being provided with an annular shoulder, and means 90 carried by the other part for engagement with said shoulder to limit outward movement of one of said parts relatively to the other, said means being movable transversely of said movement into and out of engagement with 95 said shoulder.

7. In a force-feed, hand-operated dispensing device, the combination of two telescopically arranged parts constituting a reservoir for the liquid to be dispensed, a nozzle 100 through which the liquid is dispensed from said reservoir, one of said parts being provided with an annular shoulder, and laterally displaceable means carried by the other part for engagement with said shoulder to limit outward movement of one of said parts 105 relatively to the other, said means, when displaced laterally from said shoulder permitting further outward movement of one of said parts relatively to the other. 110

8. In a force-feed, hand-operated dispensing device, the combination of two telescopically arranged parts constituting a reservoir for the liquid to be dispensed, a nozzle through 115 which the liquid is dispensed from said reservoir, one of said parts being provided with an annular shoulder, and resilient, laterally displaceable means carried by the other part for engagement with said shoulder to limit outward movement of one of said parts relatively to the other, said means being laterally displaceable by said shoulder upon the application of sufficient force in an outward direction of one of said parts relatively to the other. 120

9. In a force-feed, hand-operated dispensing device, the combination of two telescopically arranged parts constituting a reservoir for the liquid to be dispensed, one of 125 said parts having a reduced portion which,

together with the other part, is adapted to form a liquid-receiving groove open at the top to receive liquid when one of said parts is displaced inwardly relatively to the other.

5 10. In a force-feed, hand-operated dispensing device, the combination of two telescopically arranged parts constituting a reservoir for the liquid to be dispensed, the inner part having a reduced portion which, together with the outer part, is adapted to form a liquid-receiving groove open at the top to receive liquid when one of said parts is displaced inwardly relatively to the other.

10 In testimony whereof I have affixed my signature.
